Hallen Battle

Letter patent, Patented November 6, 1829.)

The Schedule referred to in the ~~Letter~~ ^{of} ~~Letter~~ Patent, & making part of the same, containing a description, in the words of the said Hallen Battle himself, of his improvement in Steam engines.

To all persons to whom these presents shall come, Hallen Battle of the city of Albany, in the County of Albany and State of New York, mechanick and engineer. Be it known, that I, the said Hallen Battle have invented a new and useful improvement or method not known, nor used before in the making or forming of steam engines applicable to navigation, the propelling of boats or other vessels, or to purposes of manufacturing, or mills of any description, and called by me, and known by the name of The reciprocating steam engine. The objects of this improvement are to lessen the quantity of fuel, to make the generator of steam more durable, less subject to explosion, more powerful, and with a less quantity of water. First. this improvement consists of four distinct branches, to be used in combination, or otherwise, as is herein after more particularly explained, and may be called 1st A new combination of the pipes, (herein after referred to) with the common high or low pressure boiler, or otherwise it may be called Reservoir. 2nd. By placing a Reservoir between the high & low pressure engines and connecting them with one shaft. 3rd By the formation of a Generating supply pipe, and 4th by the formation of a Generator in the smoke pipe. Place any number of tubes and pipes, as the power of the engine, (at a vertical or horizontal position), and in one or more ranges, either lengthwise or crosswise of the fire, connected at each end by elbows, or otherwise forming one continued pipe, or they may be placed in such a position as to admit the fire to pass about them. They should be supplied with water at one end of the ranges, either from the forced Pump, or the Reservoir, or boiler. The Reservoir or boiler may be placed above the tubes, below, or on both sides, or wholly surround the tubes, but it is preferable in my opinion, to place them in such a position, that the tubes and boiler will form a flue of sufficient length to exhaust the heat, so that the boiler or reservoir will receive its proportion of heat. The water that passes

through these pipes, which is not generated into steam, passes into the reservoir with the steam, and a greater quantity of water will gather there, than is evaporated into steam, a pipe should be placed upon the lower part of the boiler or reservoir, connected with the pipes, so that the gravity of the water will force that overplus into the pipes again. A cock should be placed in the pipe to regulate the quantity of water that is necessary to feed the pipes, and for this purpose it is necessary, that the steam pipe, which passes from the pipes to the boiler or reservoir, should enter the boiler above the surface of the water therein. In case the gravity of the water is not sufficient to return the water into the pipes again, a force-pump may be attached for that purpose. When this combination is used for burning the anthracite coal, the flue will be made shorter, and the furnace deeper than they are proposed as represented in figure D [47] and figure E [48] in the accompanying draft. Secondly, when much of the heat passes off, through the chimney, or smoke-pipe, in such form as to have the heat pipe around them, so that the steam passing through them from the boiler or reservoir to the engine will receive additional elastic force. These pipes may be made of cast, or wrought iron, or copper and form one continued pipe; or all come together, and may be applied to other boilers distinct from the before described. Thirdly, a generating or heated supply pipe may be applied to the high or low-pressure engine and boilers. This pipe passes from the forced pump into the condenser, and is there coiled up, in the form of a still-brown, or may be made with joints or elbows in such form as to coil a considerable length in the condenser; or they may be cast into such a form as to make one continued pipe so that the supply water passing through these pipes with the steam blowing direct from the engine, will give the water a high degree of heat before it passes into the boiler or generator. When this is applied to the low-pressure engine, it should be placed above the water in the condenser. When applied to the high pressure engine, it may be placed at the bottom of the condenser; and a copper pipe added to the bottom of the condenser, immered in water with a valve in the out end, and to which will cause a powerful vacuum. Fourthly. The important object in the reciprocating steam engine is attained by constructing and using an engine with two working cylinders, one high and the other low pressure, or they may be considered as two distinct engines, although

they cannot have the desired effect, unless they are connected and move the steam from the steam, and admit the steam across what is termed the dead point, and the low pressure engine, the steam from the high, but instead of running it direct as the Watt Engine does, it passes into a reservoir of suitable size, to have the steam expand with suitable elasticity, to work the low pressure cylinder, without reducing the elasticity of the steam between the intermediate strokes. There should also be a safety valve on the reservoir, so that if the steam should rise to such a temperature, as to be too high for the low pressure, the valve in that case, will admit the steam to escape. This reservoir should be enclosed or surrounded with a non conductor of heat. The two cylinders or engines, before mentioned are to work on one connected shaft with crank to stand at right angles, so that one engine turns the other across the dead point without use of the fly wheel, or at most, it will not require more than half the weight of ... fly, that a single engine does. These cylinders may be placed at any convenient distance from each other, and may be worked by a Walking beam or a cross-beam otherwise, and may be so coupled together that one may operate, and the other stand still, or one engine may work one way, and the other the other way, as is frequently necessary in steam boats to turn short at right angles. To perform this, a coupling should be placed between the engines, upon the crank shaft so that the engines may be disengaged at pleasure. To work the high without the low pressure the coupling should be disengaged and the steam to pass from the generator or boiler to the high pressure engine and blow off at the valve on the reservoir. To work the low without the high, the steam passes from the boiler to the reservoir, without passing through the high pressure cylinder, and then expands to its proper elasticity to work the low pressure engine. Explanations of the accompanying draft. Figure A represents a front view of the combined generator showing 1. 1. 1. The reservoir or boiler 2. 2. 2. The pipes 3. The door of the furnace 4. The steam pipe. Figure B represents the end view of the high pressure engine showing 5. The cylinder 6. The piston rod. 7. the walking beam 8. the reservoir. Figure C represents a front view of the low pressure engine showing 9. The cylinders. 10. the piston rod. 11. the walking beam 12. the condenser. 13. The connecting or crank shaft. 14. 14. the gallows frame. Figure D represents a side view of the combined generator, showing 15. the reservoir or boiler 16. the heated pipe 17. the furnace 18. the horizontal tubes. 19. the steam pipe from the heated pipe to the reservoir 20. 20. ~~the~~ ^{the} bottom or lower part of the reservoir & boiler. 21. The double pipe. Figure E represents the condenser and heated supply pipe showing 22. 22. The condenser 23. heated pipe. Figure F represents a side view of the double engine showing 24. The walking beams. 25. the cylinder (low pressure) 26. The valve. 27. The gallows ... frame. 28. the air pump 29. the fire pump. 30. the fly wheel. 31. Cranks. Figure G represents a front view of the generating, smoke pipe together with the boiler.

for low pressure or low pressure engine. Having 23 the passing, back pipe, 24 the return for steam and water 25:26 the heated pipe, and connecting pipe with return in 25. One of furnaces 26, being round the pressure. Figure 27 represents a side view of boiler or generator for low pressure and low pressure engine, having 27 return for steam & return 28. Heated pipe, 29. Connecting pipe with the return, 30. furnace. Figure 28 represents an end view of the generating back pipe. In witness whereof I have hereunto subscribed my name the 13th day of October 1821.
